LOCK

Filed Aug. 29, 1929

INVENTOR.
ARTHUR CLAUD-MANTLE.
BY
Arthur Claud-Mantle
ATTORNEY.

UNITED STATES PATENT OFFICE

ARTHUR CLAUD-MANTLE, OF BRIDGEPORT, CONNECTICUT, ASSIGNOR TO THE BASSICK COMPANY, OF BRIDGEPORT, CONNECTICUT

LOCK

Application filed August 29, 1929. Serial No. 389,128.

The present invention relates to latches, particularly for automobile doors, and has for an object to provide a latch in which the handle shaft is adapted to be secured in such relation to the latch that it cannot be removed by unauthorized persons, when the latch is locked, should such persons succeed in disengaging the escutcheon plate, which is ordinarily the only means for retaining the handle against longitudinal movement. A further object is to provide a construction in which the handle shaft may be inserted into relation with the latch during assembly of the automobile with facility, and without the necessity for employing special tools, keys, and the like. Another object is to provide a device of this character which may be attached to the bolt and handle shaft, without changing or affecting the other parts of the latch.

With the above and other objects in view, an embodiment of the invention is shown in the accompanying drawing, and this embodiment will be hereinafter more fully described with reference thereto, and the invention will be finally pointed out in the claims.

In the drawing:

Fig. 1 is a plan elevation of an automobile door latch, according to the present embodiment of the invention, the handle shaft being shown in section.

Fig. 2 is a vertical sectional view, taken along the line 2—2 of Fig. 1, and showing the latch in its relation in the door.

Fig. 3 is a side elevation of the handle and shaft employed.

Fig. 4 is an inner end view thereof.

Fig. 5 is a fragmentary plan elevation, and showing the relation of the parts with the bolt retracted.

Similar reference characters indicate corresponding parts throughout the several figures of the drawing.

Referring to the drawing, the exemplary latch embodying the present improvements comprises a base plate 10 provided with a flange 11 at its forward end having a latch bolt opening therein. The latch bolt 13 is

slidably engaged at its nose end 14 in the opening 12, and retained against displacement by means of a cover plate 15 secured to the base plate. A coil spring 16 engaged with the inner end of the bolt normally presses it to its projected position.

At the rearward end of the bolt there is provided an upwardly projecting vertical extension 17 engaged by the inside handle roll-back 18, the hub 19 of which has bearing in apertures formed in the base and cover plates 10 and 15. A coil spring 20 normally engaged at one end with a lug 21 on the roll-back, and engaged at its other end against a lug 22 struck from the base plate yieldably retains the roll-back in its normal position by engaging a projection 23 thereon with the lug 22.

The outside handle roll-back 24 has its hub 25 rotatably engaged in apertures in the plates 10 and 15, and is adapted to actuate the bolt through engagement with an upwardly and forwardly projecting arm 26 formed on the bolt.

The handle 27 is provided with the usual escutcheon plate 28 secured thereto, and a key operated lock 29, adapted in the locked position to engage with a locking dog 30 secured in the door to prevent rotation of the handle. A shaft 31, of square cross-section, is secured to the handle and is adapted to fit the square opening 32 of the roll-back. In the usual type of lock it is possible in the locked relation to unscrew the escutcheon plate and then withdraw the handle, whereupon a plane square shaft may be inserted in the roll-back and the latch operated to open the door. The present improvements are intended to prevent such unauthorized withdrawal of the handle shaft and opening of the door.

Upon one side of the shaft 31 and in spaced relation to the end, a projecting pin or lug 33 is provided, and which is adapted in the assembled relation, as shown in Figs. 1 and 2, to be rotatably disposed beneath the projected upper end of a plate 34 secured to the bolt 13 by rivets 35. In the locked relation of the handle, with the bolt projected, the pin 33 is beneath the end of the plate 34, and withdrawal of the handle shaft is prevented.

As the locking of the

handle prevents relative rotary movement of the shaft, rotation of the shaft to turn the pin from beneath the plate is impossible, even though the escutcheon is unscrewed.

5. In order to assemble the handle it is only necessary to retract the bolt by means of the inside handle roll-back, or by pressing it in at the nose end, as shown in Fig. 5, or it may be retracted by engaging the end of the 10 handle shaft in the outside handle roll-back, and then turning the roll-back to a point where the plate 34 is out of the path of the pin 33, whereupon the handle shaft is pressed into position so that the pin will be beneath the plate when the bolt is again projected. 15 Upon insertion of the handle shaft the escutcheon and lock is secured in the usual manner to the door front.

I have illustrated and described a preferred 20 and satisfactory embodiment of the invention, but it will be obvious that changes may be made therein, within the spirit and scope thereof, as defined in the appended claims.

Having thus described my invention, what 25 I claim and desire to secure by Letters Patent is:—

1. In a latch, a latch casing, a latch bolt, a roll-back carried by said casing for retracting said bolt, a removable handle shaft adapted 30 to be longitudinally engaged with said roll-back and including an abutment portion, abutment means carried by the latch bolt adapted to abut said abutment of the handle shaft upon longitudinal withdrawal 35 movement in the normal non-bolt-retracting position of said roll-back, said abutment means adapted to permit longitudinal engaging movement of the end of said handle shaft with said roll-back and rotary movement of 40 said handle shaft in any position of said roll-back and in any position of rotation of said handle shaft.

2. In a latch, a latch casing, a latch bolt, a roll-back carried by said casing for retracting said bolt, a removable handle shaft adapted 45 to be engaged with said roll back in any position of rotation of said handle shaft and roll-back, and cooperating means respectively carried by said handle shaft and latch bolt 50 adapted in the projected position of said bolt to prevent longitudinal withdrawal movement of said handle shaft.

3. In a latch, a latch casing, a latch bolt, a roll-back for retracting said bolt, a handle 55 shaft adapted to be engaged with said roll back and including a lateral abutment spaced from the end, and abutment means carried by said bolt adapted in the projected position of said bolt to abut said abutment of the shaft 60 upon longitudinal withdrawal movement thereof.

4. In a latch, a latch casing, a latch bolt, a roll-back for retracting said bolt, a handle 65 shaft adapted to be engaged with said roll- back and including a lateral abutment spaced

from the end, and abutment means secured to and movable with said bolt adapted in the projected position of said bolt to abut said abutment of the shaft upon longitudinal withdrawal movement thereof.

5. In combination, a latch including a latch casing, a latch bolt, and a roll-back carried by said casing for retracting said bolt, a removable handle shaft adapted to be engaged with said roll-back in any position of rotation of 75 said handle shaft and roll-back and to be turned to rotate said roll-back, locking means associated with said shaft adapted to be actuated to prevent rotation of said shaft, and means cooperating between said latch bolt and handle shaft adapted in the locked relation of 80 said handle shaft to prevent longitudinal withdrawal movement thereof.

6. In combination, a latch including a latch casing, a latch bolt, and a roll-back for retracting said bolt, a handle shaft adapted to be engaged with said roll-back and to be turned to rotate said roll-back, locking means associated with said shaft adapted to be actuated to prevent rotation of said shaft, 85 and means cooperating between said latch and handle shaft adapted in the locked relation of said handle shaft to prevent longitudinal withdrawal movement thereof, and adapted in the unlocked relation of said handle to 90 permit of longitudinal insertion in the roll-back in any position of said roll-back.

Signed at Bridgeport, in the county of 95 Fairfield, and State of Connecticut, this 20th day of August, 1929.

ARTHUR CLAUD-MANTLE.
